(57) **CLAIM**

The ornamental design for a power supply assembly for electronic atomization device as shown and described.

DESCRIPTION

FIG. 1 is a perspective view of a power supply assembly for an electronic atomization device showing our design; FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is an enlarged view of area 9 circumscribed in FIG. 1;

FIG. 10 is a perspective view of the power supply assembly shown as a component 1 removed from the assembly in FIGS. 1–9 for clarity of disclosure;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is an enlarged top plan view thereof;

FIG. 17 is an enlarged bottom plan view thereof;

FIG. 18 is a perspective view of the power supply assembly shown as a component 2 removed from the assembly in FIGS. 1–9 for clarity of disclosure;

FIG. 19 is another perspective view thereof;

FIG. 20 is a front elevational view thereof;

FIG. 21 is a rear elevational view thereof;

FIG. 22 is a left side elevational view thereof;

FIG. 23 is a right side elevational view thereof;

FIG. 24 is an enlarged top plan view thereof; and,

FIG. 25 is an enlarged bottom plan view thereof.

The broken lines consisting of evenly spaced short dash lines in the drawings depict portions of the power supply assembly for electronic atomization device that form no part of the claimed design.

The broken lines consisting of long and short dash lines in the drawings depict the boundaries of the enlarged views and form no part of the claimed design.
